UNITED STATES PATENT OFFICE.

GEORGE A. CHAMBERLAIN, OF GREENE, NEW YORK.

DESIGN FOR A CHECKREIN-HOOK PLATE.

SPECIFICATION forming part of Design No. 27,243, dated June 22, 1897.

Application filed April 24, 1897. Serial No. 633,814. Term of patent 7 years.

To all whom it may concern:

Be it known that I, GEORGE A. CHAMBERLAIN, a citizen of the United States, residing at Greene, in the county of Chenango and State of New York, have invented and produced a new and original Design for Checkrein-Hook Plates; and I do hereby declare the following to be a full, clear, and exact description of the same, reference being had to the accompanying drawings, forming a part thereof.

My invention relates to a new and original design for a checkrein-hook plate; and the object is to provide a design of this character that should be both useful and ornamental.

My invention relates to the entire configuration of the checkrein-hook plate, and particularly to the design as illustrated in the accompanying drawings, in which—

Figure 1 is a perspective view of a checkrein-hook plate embodying my design. Fig. 2 is a top plan view. Fig. 3 is a side elevation.

The leading features of my design appear in the following description:

1 represents the plane rectangular base- 25 plate provided with a circular orifice 2. 3 3 represent parallel arms extending forwardly and upwardly and connected at their forward ends by a transverse bar 4, and 5 represents a cylindrical sleeve mounted on 30 said bar 4.

Having thus fully described my invention, what I claim as new, and desire to secure by Letters Patent of the United States, is—

The design for a checkrein-hook plate sub- 35 stantially as herein shown and described.

In testimony whereof I affix my signature in presence of two witnesses.

GEORGE A. CHAMBERLAIN.
